UNITED STATES PATENT OFFICE

2,087,220

FIRE HYDRANT

Hugh Thomas Dunn, New York, N. Y.

Application September 4, 1935, Serial No. 39,102

1 Claim. (Cl. 137—13)

This invention relates to fire hydrants.

The object of the invention is the production of a fire hydrant, which when frozen can easily have conduits formed through the ice therein, to 5 secure the immediate and efficient operation of the hydrant.

In the accompanying drawing, Fig. 1 represents a vertical cross section with portions in full lines of an exemplification of the improved 10 hydrant; Fig. 2 shows a section of Fig. 1 on the line 2—2 and Figs. 3 and 4 indicate elevations of details.

The hydrant is indicated to comprise the barrel casing 1, having a horizontal flange at its 15 lower end which bears on the outer surface of a water main 18, and is fastened thereto by bolts 28. The said flange has an opening therethrough which forms a valve seat indicated at 14. A drain outlet fitting 17, is provided for the lower end of the casing. A head for the barrel casing 1, is indicated at 2. Said head has openings therethrough as shown, and is detachably fastened to the casing by bolts as indicated in 20 Fig. 1. Pairs of horizontal slightly tapered outlets 30, extend from the barrel casing 1, near its top end.

An operating shaft is indicated with the upper cylindrical member 3, having the longitudinal threaded opening 4. The member 3 at its 30 upper end is indicated having the head 23 which joins with a disc flange indicated in the drawing. A stuffing box 5 extends from the lower face of the head 2, and through which the member 3 extends. A collar 11 is fastened to the 35 member 3 adjacent to the lower face of the stuffing box 5. A valve stem is shown with its upper threaded portion 9 which is in threaded engagement with the threaded opening 4. A square portion 10 for the valve stem extends from the 40 portion 9. Collars 13 and 25 are provided to said square portion 10. The lower end of the square portion 10 joins with a threaded cylindrical portion as shown in Fig. 1. A valve 15 is supported on said threaded cylindrical portion by means of the nut 16. A web 12 having a square opening is shown in the barrel casing 1. The said square portion 10 extends through the opening of the web 12. A socket wrench 21 is provided for the head 23.

A slightly tapered, spirally grooved, tubular vertical shaft 24, is indicated with the cap 7, at its upper end and from the latter extends the head 8. A screw plug 27 is provided for the lower end of the shaft 24. Spiral groove 32 is 5 indicated on the outer surface of the shaft 24. The said shaft 24, extends through the head 2, into the barrel casing 1, and the cap 7, is in threaded engagement with the head 2.

For the horizontal outlets 30 are indicated 10 the short slightly tapered spirally grooved horizontal shafts 6, having the caps 7 with the heads 8. The spiral grooves for the shafts 6 are shown at 32, Fig. 3.

Hose connections are indicated at 22 for the 15 outlets 30.

The operation of the invention is as follows:

When the water 26, in the casing 1, is frozen, the cap like 7, of the spirally grooved vertical shaft 24, is unscrewed from the head 2. Then 20 the head 8 of the cap 7, is struck with a hammer and the like. By this means the spirally grooved shaft 24, can be lifted from frozen water or ice 33, and there will be left a conduit for water, like 31. A hose connection like 22, may then be connected to the head 2, to coat with the water 25 conduit produced or an auxiliary cap like 29, may be screwed to the head 2. Also the short slightly tapered spirally grooved horizontal shafts 6, may be removed from the frozen water 30 or ice 33, as described for the shaft 24, and hose connections connected to the horizontal outlet 35 30 as indicated at 22.

It is to be understood that in addition to the 40 hose connection for the conduit 31, a similar hose connection may be connected to the head 2, for the parallel conduit made by the shaft 24, which in the drawing is shown in the ice of the casing. In fact hose connections may be applied for the two vertical outlet conduits that are produced, 45 and four hose connections may be connected for the four horizontal outlet conduits like 30.

Having described my invention I claim:

In a fire hydrant, an outlet cap having a spirally grooved tapering shaft connected thereto for the purpose set forth.

HUGH THOMAS DUNN.
